UNITED STATES PATENT OFFICE.

ALBERT L. WATSON AND GEORGE L. BARDEN, OF PENN YAN, NEW YORK.

FEEDING MECHANISM.

Application filed October 31, 1924. Serial No. 747,007.

This invention aims to provide novel means whereby a plurality of strips may be fed or advanced longitudinally, into crossed and overlapped relation, on top of a hoop, in some instances, but not necessarily, to be fastened together, and to be fastened to the hoop, if a hoop is used, by staples or otherwise, the device being of peculiar utility in making basket covers, basket parts, baskets and similar articles.

It is within the province of the disclosure to improve generally and to enhance the utility of devices of that type to which the invention appertains.

Although a preferred form has been shown, it will be understood that a mechanic, working within the scope of what is claimed, may make alterations, without departing from the spirit or placing the utility of the device in jeopardy.

In the accompanying drawings:—

Figure 1 shows in top plan, a device constructed in accordance with the invention; Figure 2 is a front elevation showing certain of the chutes, parts being broken away; Figure 3 is a rear elevation disclosing one of the chutes, parts being broken away; Figure 4 is a vertical longitudinal section taken through one of the chutes and attendant parts, the chute being broken away intermediate its front and rear ends; Figure 5 is a section taken about on the line 5—5 of Figure 3, parts being omitted, and the view being introduced for the purpose of showing the member which upholds the rear end of the slat or strip in the chutes when the feeder is advanced;

Figure 6 is a sectional view of the front portion of one of the chutes; Figure 7 is a diagrammatic view illustrating in plan the mechanism whereby motion is transmitted to the feeders of the chutes from the pressure-actuated piston; Figure 8 is an elevation depicting the valve mechanism, in relation to the stapler and other parts; Figure 9 is a sectional view taken through a portion of the table and disclosing, in elevation, the support which upholds the strips whilst the feeders are being withdrawn, and when the strips have been advanced upon the table, as shown in Figure 1; Figure 10 is a cross section taken through that portion of the machine which is delineated in Figure 9.

In carrying out the invention, there is provided a support 1, which may be constructed in various ways. According to the draw-

ings, the support 1 embodies a base 2, above which are located chutes 3, 4, 5, 6 and 7. The chutes are supported from the base 2 on legs 8, or in any other suitable way. The chutes 3 and 4 are disposed side by side, as are the chutes 6 and 7, the chute 5 being located between the chutes 4 and 6, in spaced relation thereto, as Figure 1 will disclose, all of the chutes being disposed radially with respect to a central point, which is the vertical center of a table 39, hereinafter alluded to.

At their lower edges, the chutes 3, 4, 5, 6 and 7 are provided with longitudinal guides 9, carrying the sides 10 of the chutes. The sides 10 of the chutes are connected by a rear wall 11 and a front wall 12. Hangers 14 are secured to the rear end walls 11 of the chutes and have annular fingers 15, extended horizontally and forwardly into the chutes, as shown in Figure 5. The fingers 15 serve to support the rear ends of the strips 16 in the chutes, whilst the lowermost strip is being advanced forwardly out of each chute, by a mechanism now to be described.

Each chute is supplied with a horizontally slideable bottom or feeder 17, mounted for reciprocation in the guides 9, and carrying longitudinal retainers 18 which slide in the guides. The parts 18 are called retainers, because they cooperate with the longitudinal edges of the lowermost strip 16 in each chute, whilst the strip is being advanced out of the chute.

Each feeder 17 is provided intermediate its longitudinal edges with an upstanding rib 19, equipped at its rear end with an upstanding shoulder 20. (Figures 2 and 1). The strips 16 sometimes are warped, and if they are warped, the rib 19 supports them along their longitudinal centers. The upstanding shoulder 20 on the rear or outer end of the rib 19 is adapted to engage the rear end of the lowermost strip 16 in each chute, so as to move the strip forwardly upon the table 39, when the feeder 17 is advanced. In their rear ends, the feeders are provided with slots 21 which receive the fingers 15 of the hangers 14 and permit the feeders 17 to be advanced and retracted. Transverse cleats 22 are secured to the rear ends of the feeders 17 and serve to offset any weakening caused by the slots 21, the cleats being cut away as at 23 in Figure 2, to clear the guides 9, wherever necessary. The cleat 22 which is located beneath the chutes 3 and 4 has at-

tached thereto an anchor block 24, an anchor block 25 being similarly mounted on the cleat of the feeder of the chute 5, and an anchor block 26 being mounted on the cleat 5 of the feeders of the chutes 6 and 7. At this point, it will be profitable to glance at Figure 7, in comparison with Figure 1.

Noting Figures 2 and 4, it will be observed that a horizontal lip 27 is struck forwardly from the front end wall 12 of each chute. In the lip 27 is mounted (Figure 4) an adjusting device 28, such as a vertical bolt, carrying a nut 29 engaging the lip 27, the lower end of the bolt being mounted on a forwardly extended projection 30 constituting a part of a vertically adjustable stop 31, movable, for adjustment, in guides 32 attached to the front end wall 12 of each chute. The stop 31 projects downwardly below the wall 12, as in Figure 4, and holds back the next to the bottom strip 16, whilst the bottom strip is being advanced by the shoulder 20 of the feeder 17. Through the instrumentality of the nut 29 and the bolt 28, the stop 31 may be adjusted vertically, the stop being held against upward movement, yieldably, by a compression spring 33, interposed between the projection 30 of the stop 31 and the lip 27 on the front wall of the chute 12.

After the strips have been advanced by the shoulders 20 of the feeders 17, into the positions shown at 42, 43 and 44 in Figure 1, it is desirable to hold the strips in that position whilst the feeders 17 are being retracted. Having this consideration in mind, dogs 34 are pivoted to the front walls 12 of the chutes 3, 4, 6 and 7, and knuckle against the walls 12, so that the dogs cannot swing downwardly beyond the position which they occupy in Figure 4. The dogs 34 are used at the forward end of the chutes 3, 4, 6 and 7, as aforesaid. On the front wall of the intermediate chute 5, a different sort of dog, marked by the numeral 35, and shown in Figure 6, may be used. The dog 35 has a vertical stem 36 mounted to slide in the guides of the intermediate chute, and pressed downwardly by a compression spring 38, engaged at its upper end with one of the guides, and engaged at its lower end with an abutment 37 on the stem 36 of the dog. The dogs 34 drop by gravity behind the rear ends of the strips, after the strips have been advanced into the position shown at 42-43 in Figure 1, the dog 35 being forced downwardly by the spring 38, into a corresponding position with respect to the rear end of the strip 44 of Figure 1. The reason for the difference in the construction and operation of the dogs 34 and 35 is that there is considerable space between the forward end walls of the chutes 3-4 and 6-7, on the one hand, and the table 39, on the other hand, whereas there is not so much space between

the forward end of the chute 5 and the table, it being desirable, therefore, to give the dog 35 a somewhat quick downward movement, through the instrumentality of the spring 38.

The table 39, hereinbefore alluded to, is supported in any suitable way on the base 2 and has an upstanding annular rim 40, which is seen best in Figures 4 and 10. The hoop 41, to which the strips are to be stapled, or secured otherwise, after they have been advanced into the positions shown at 42-43-44, is mounted on the table 39, within the rim 40, the strips being advanced across the upper edge of the hoop. Within the rim 40 of the table 39 is disposed an arcuate support 45 having, in its upper edge, seats 46, 47 and 48, as disclosed in Figure 9. The seats 47 and 48 receive the outer ends of the strips 43, and the seat 46 receives the outer end of the strip 44. The support 45 is provided, in order that when the feeders 17 are retracted, no one feeder will pull the adjoining strips crosswise and out of place. The support 45 has depending plungers 49, 50, surrounding the plungers, and interposed between the support 45 and the table 39. Owing to the presence of the springs 50, the support 45 can move downwardly, when the stapler 51 of Figures 1, 4 and 8 is fastening the strips 44, 42 and 43 together, and fastening them to the upper edge of the hoop 41 which is located within the rim 40 of the table 39. The stapler 51 may be of any desired construction, and is moved vertically above the table 39 by any suitable means, there being no detailed showing of the stapler because it is a device purchased in the open market and forming no part of the present invention, aside from the fact that it has a function in operating the valve mechanism depicted in Figure 8. An angular (Figure 1) arm or keeper 52 (Figure 8) is secured to the vertically movable stapler 51.

A post 53 is erected on the base 2, and is disposed near to the free end of the keeper 52 on the stapler 51, the post carrying a guide 55 wherein a latch 54 is mounted for swinging movement, a compression spring 56 being located in the guide 55 and serving to swing the latch 54 to the right in Figure 8, so that when the stapler 51 moves downwardly, the keeper 52 on the stapler can first swing the upper end of the latch 54 to the left in Figure 8, and then engage beneath a shoulder 57 on the latch, to raise the latch when the stapler 51 moves upwardly. In order to disengage the shoulder 57 of the latch 54 from the keeper 52 on the stapler 51, after the stapler has moved upwardly a predetermined amount, the latch 54 has a beveled edge 58 adapted to engage a releasing projection 59 on the post 53. The lower end of the latch 54 is pivoted to a

bell crank lever 60, mounted for swinging movement on the post 53.

A horizontal cylinder 61 is mounted on the base 2, and in the cylinder, a piston 62 reciprocates. The piston 62 may be operated by air, steam or any other fluid, but it will be assumed hereinafter that the piston is steam actuated. The piston 62 carries a cross head 63 (Figures 1 and 8) mounted to slide on guide rods 64 supported at their rear ends on the cylinder 61, the cross head having an upstanding arm 72. Pulleys 65, 66, 67, 68, 69 and 70 are supported for rotation, by any suitable means indicated at 77. A flexible element 71 is connected to the block 26 of the feeders 17 for the chutes 6 and 7 and is looped about the pulley 70, the flexible element being connected to the arm 72 on the cross head 63 of the piston 62 and being looped about the pulley 65. From the pulley 65, the flexible element is continued to the anchor block 24 of the feeders 17 for the chutes 3 and 4, and from the anchor block 24, the flexible element extends about the pulleys 65, 67 and 68, to the pulley 69, the anchor block 25 of the feeder 17 for the intermediate chute 5 being connected to the flexible element 71—all as indicated in Figure 7. Although the part 71 has been alluded to as a flexible element, in the singular number, it will be understood that it may be made up of as many portions as is desired, in order to facilitate connection to the anchor blocks 24, 26 and 23. As shown in Figure 1, the pulley 65 is located at the inner end of the chute 3, the pulley 66 being placed at the outer end of the chute 4, the pulley 67 being disposed at the inner end of the chutes 4 and 5, the pulley 68 being journaled at the outer end of the chute 5, the pulley 69 being rotatably mounted at the inner end of the chute 6, and the pulley 7 being supported at the outer end of the chute 6.

Steam is admitted into the cylinder 61 and is exhausted from the same by means of a D-valve 73, which need not be described in detail, because its construction is familiar to those having even an elementary knowledge of steam engine construction. The valve 73 is operated by a rod 74 provided at its outer end with a transverse finger 75, disposed in the path of the arm 72 which is carried by the cross head 63 on the piston 62. A link 76 is pivoted at one end to the bell crank lever 60, and at the other to the valve rod 74.

When the parts are arranged as shown in Figure 8, the valve 73 is so positioned that steam has entered the forward end of the cylinder 61, and the steam in the rear end of the cylinder has been exhausted. The piston 62 has been retracted, the flexible element 71 retracting the feeders 17 in the chutes 3, 4, 5, 6 and 7, the shoulders 20 on

the ribs 19 of the feeders engaging the rear ends of the lowermost strips 16 in the chutes, and the strips 42, 43 and 44 being in place on the hoop 41, as shown in Figure 1. The stapler 51 now moves downwardly and fastens the strips 42, 43 and 44 together, and to the hoop 41, the support 45 moving downwardly, and the springs 50 being compressed, as the stapler descends.

The operator now removes the finished product from the table 39 and inserts a new hoop 41 within the rim 40 of the table. As the stapler 51 descends, the keeper 52 on the stapler engages beneath the shoulder 57 of the latch 54, and raises the latch when the stapler moves upwardly, the beveled edge 58 of the latch engaging the projection 59 on the post 53 and disengaging the latch from the stapler, after the stapler has moved upwardly a predetermined distance. When the latch 54 is raised, as aforesaid, the bell crank lever 60 is tilted, and the link 76, co-operating with the valve rod 74, shifts the valve 73 to the left in Figure 8, so that the steam in the forward end of the cylinder 61 is exhausted, steam being admitted to the rear end of the cylinder, the piston 62 being advanced, and the flexible element 71 advancing the feeders 17, the shoulders 20 of the feeders advancing the lowermost strips 16 out of the chutes 3, 4, 5, 6 and 7, into the position shown at 42—43—44 in Figure 1, ready to be stapled together and the hoop 41, when the stapler 51 descends. As the piston 62 arrives at the end of its forward stroke, the arm 72 on the cross head 63 of the piston engages the finger 75 on the valve rod 74 and shifts the valve 73 so that the steam in the rear end of the cylinder 61 is exhausted, steam entering the forward end of the cylinder and causing the piston to move rearwardly, the flexible element 72 retracting the feeders 17 into the chutes 3, 4, 5, 6 and 7, and the strips 42, 43 and 44 being held in the position of Figure 1, by the dogs 34 and 35, against the backward drag of the feeders 17. When the valve rod 74 is moved to the right in Figure 8, by the engagement between the arm 72 on the piston 62 and the finger 75 on the valve rod 74, as the piston is advanced, the link 76 and the bell crank 61 draw the latch 64 downwardly into the position of Figure 8, so that when the stapler 51 moves downwardly, and then upwardly, the keeper 52 on the stapler may engage with the shoulder 57 and raise the latch as hereinbefore explained. An interval elapses between the time that the valve 73 is moved by the engagement between the parts 72 and 75, and the shifting of the valve by the parts 51—52—57—54—60 and 76, and during this interval, the piston is moved to the left in Figure 8, and then is held at rest, by the steam in the forward end of the cylinder 61.

It will be understood that the stapling mechanism may be so located as to connect the overlapped strips to the hoop, or to connect the overlapped strips together, independently of the hoop, as the operator may prefer.

Having thus described the invention, what is claimed is:—

1. In a device of the class described, a hoop-supporting table having an upstanding rim within which a hoop is adapted to be placed, chutes disposed in substantially radial relation to the table, feeders movable in the chutes, and means for actuating the feeders.
2. In a device of the class described, a hoop-supporting table provided with an upstanding rim within which a hoop is adapted to be placed, a support within the rim and having seats for the reception of the strips which are to be fastened to the hoop, strip-holding chutes cooperating with the table, and feeders movable in the chutes and adapted to advance the strips out of the chutes, upon the table, and into the seats of the support.
3. A device of the class described, constructed as set forth in claim 2, and further characterized by the provision of means for carrying the support resiliently on the table.
4. In a device of the class described, a strip-receiving chute, a feeder mounted to reciprocate in the chute and constituting means for advancing a strip out of the chute, a table whereon the strip is advanced, a hoop-holding means on the table, yieldably supported means assembled with the table for upholding the outer end of the strip with respect to the hoop-holding means, and movable means coacting with the inner end of the strip to hold the strip against retraction when the feeder is retracted.
5. In a device of the class described, a table, chutes disposed in substantially radial relation to the table, feeders slidable in the chutes and adapted to advance strips out of the chutes and upon the table, a flexible element connected to the feeders, direction-changing idlers wherewith the flexible element is engaged, and mechanism for actuating the flexible element.
6. A device of the class described, constructed as set forth in claim 5, and further characterized by the fact that said mechanism embodies a fluid-pressure cylinder and a piston operating in the cylinder, the flexible element being connected to the piston.

7. In a device of the class described, a table, strip-holding chutes, feeders movable in the chutes and adapted to advance strips out of the chutes and upon the table, mechanism for operating the feeders, said mechanism comprising a fluid-pressure cylinder and a piston operating therein, a valve controlling the fluid-pressure supply for the cylinder, means operated by the piston for shifting the valve in one direction, movable means for fastening the strips, and mechanism operated by said movable means for shifting the valve in an opposite direction.

8. In a device of the class described, a hoop-supporting table provided with an upstanding rim within which a hoop is adapted to be placed, a support within the rim and having seats for the reception of the strips which are to be fastened to the hoop, means for automatically feeding strips into the seats of the support, across each other at a common center, and means for fastening the strips together at their place of crossing.

9. In a basket making machine, means for automatically feeding separately a plurality of angularly disposed strips in the direction of their length in such a manner that when the strips are fed they will be disposed across each other and the ends thereof will radiate from a common center, and means for applying a fastening to the strips where they cross each other.

10. In a basket making machine, means for automatically feeding separately a plurality of angularly disposed strips in the direction of their length in such a manner that when the strips are fed they will be disposed across each other and will extend in a general radial direction from a central area, and means for applying a fastening to the strips where they cross each other.

11. In a basket making machine, means for automatically feeding a plurality of strips separately in an angularly disposed relation and in such manner that when the strips are fed they will be disposed in crossing relation and having their ends outwardly directed from a central area and approximately lying in one general plane, combined with means for mechanically fastening the strips where they cross each other.

In testimony that we claim the foregoing as our own, we have hereto affixed our signatures.

ALBERT L. WATSON.
GEORGE L. BARDEN.
